John Leahy Jun.

JOHN SEALY, JUNIOR, OF NEWARK, NEW JERSEY.

Design No. 3,321, dated January 5, 1869.

DESIGN FOR THE ORNAMENTS OF A HAT OR CAP.

The Schedule referred to in these Letters Patent and making part of the same.

To all whom it may concern:

Be it known that I, JOHN SEALY, Junior, of the city of Newark, in the county of Essex, and State of New Jersey, have invented or produced a new Design of an Ornament for Hats, of which the following, taken together with the accompanying drawing, is a full, clear, and exact description.

A button, presenting four angular faces, and formed of metal, is attached to the crown of the hat, as at Figure 1, and an endless eccentric ellipsis band, with a circular centre, fastened to the side, close to the brim of the hat, as at Figure 2.

What I claim, and desire to secure by Letters Patent, is—

The design of the ornaments for hats herein set forth.

JOHN SEALY, JUNIOR.
